ACCUMULATOR FOR ACCOUNTING MACHINES

Samuel Brand, Binghamton, James M. Cunningham, Endicott, and Leon C. Bishop, Binghamton, N. Y., assignors to International Business Machines Corporation, New York, N. Y., a corporation of New York

Application May 13, 1946, Serial No. 669,258

5 Claims. (Cl. 235—61.6)

1

The present invention relates to record controlled calculating machines and more particularly to the accumulating mechanism thereof.

The principal object of the invention is to provide an improved accumulating structure in which two amounts may be concurrently entered to obtain their sum or difference.

A further object of the invention is to provide improved tens carry control devices responsive to concurrent entries in an accumulating structure of the type specified.

The accumulator of the present invention comprises a series of denominational ordered adding wheels each having twenty rotative positions, each of which has differential gear connection to a pair of entering wheels. The latter are separately advanced differential extents, concurrently, to receive two amounts and through the differential gear connections the adding wheels will accordingly be driven to represent thereon the combined advance of the related pairs of entering wheels. Such advance takes place during the usual entering portion of an accounting machine cycle. Contacts set by the adding wheels are effective during the later carry portion of the machine cycle to cause a step of advance of one entering wheel of higher order or a step of advance of both entering wheels of higher order to thereby advance the higher order adding wheel one or two steps, depending upon whether there is a single or double carry required.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a side elevation of the dual accumulating unit.

Fig. 2 is a detail of the readout structure.

Fig. 3 is a detail of part of the carry mechanism.

Fig. 4 is a central section through the accumulator taken substantially along lines 4—4 of Fig. 6.

Fig. 4a is a section taken on line 4a—4a of Fig. 4.

Fig. 5 is a detail of one of the drive clutch devices in operative position.

Fig. 5a is a view similar to Fig. 5 with the devices in inoperative position.

Fig. 6 is an end elevation looking from the left of Fig. 1 with the central structure shown in section.

2

Figs. 7a and 7b taken together constitute a wiring diagram containing the necessary elements for operating the accumulating structure.

Fig. 8 is a timing diagram of the related cam controlled contact devices.

Referring to the drawings, 10 represents the main drive shaft which, through suitable gearing not shown, drives card feed rollers represented diagrammatically at 11 in Fig. 7b, so that a record card C is moved past a row of sensing brushes LB for each revolution of shaft 10. The record card C is provided with the usual rows of ten index point positions wherein perforations are made to represent amounts. To obviate a detailed explanation of the well known card feeding mechanism, it will be assumed, for the purposes of the present invention, that the record card C is initially brought to a position as indicated in Fig. 7b with the brushes LB in readiness to traverse the card, and that the shaft 10 is thereafter turned through a single revolution. This revolution is represented on the time chart of Fig. 8, which indicates that the cycle is subdivided into sixteen so-called "index points" during which several cam controlled contacts operate during the periods indicated by heavy lines in the diagram.

Shaft 10 has secured thereto two drive gears designated 12L and 12R (Fig. 6) for each denominational order of the accumulating mechanism. These two gears drive similar adding devices which will hereinafter be distinguished as the left and right sections of the accumulator.

Referring to Figs. 1, 5 and 6, gear 12R drives gear 13R through the ratio of 16:10. This gear 13R is integral with a ratchet 14R freely rotatable on a sleeve 15. Lying in the plane of ratchet 14R is a dog 16R which is pivoted at 17R to a notched detenting disk 18R engaged by a spring pressed detenting lever 19R to positively restrain the disk against rotation. Between dog 16R and disk 18R is a toothed disk 20R freely rotatable on a hub of ratchet 14R. A camming surface 21R of the disk 20R engages a pin 22R in the dog 16R to hold the dog out of engagement with ratchet 14R, as shown in Fig. 5a, wherein disk 20R is shown displaced clockwise with respect to disk 18R, a spring 9R extending between the free end of dog 16R and disk 18R tends to urge disk 20R in a counter-clockwise direction against which the disk is normally restrained by a tooth on lever 23R, which engages a tooth in the disk as indicated in Fig. 5a. When lever 23R is rocked out of engagement with the disk, the latter will rotate

counterclockwise to the position of Fig. 5 under the influence of spring 9R, causing the dog 16R to engage the ratchet for driving action thereby. Thereafter, if lever 23R is rocked back to its position of Fig. 5a, it will engage one of the teeth of disk 20R to hold it while the ratchet continues to drive disk 18R through the dog 16R. This relative movement of the two disks will cause the camming surface 21R to rock the dog back to the position of Fig. 5a, wherein the parts will remain until lever 23R is again rocked downwardly. The detenting lever 19R will hold disk 18R against movement until the clutch connection is again effected.

Referring to Fig. 1, the lever 23R is pivoted to a rod 24 and has a bifurcated extension engaging the free end of an armature 25R extending between a start magnet designated STR and a stop magnet designated SPR. Energization of magnet STR will rock lever 23R to the position of Fig. 5, where it will be held by a detenting lever 26R, and energization of magnet SPR will rock it back to its initial position. The disk 18R has ten rotative positions and through the successive operation of the start and stop magnets can be advanced from any of these positions to any other. Thus, if the disk is to be advanced, let us say four steps, the start magnet STR is energized and rotation of the disk commences. When it has advanced four steps, the stop magnet SPR is energized to effect uncoupling and the disk will accordingly come to rest after having advanced four steps.

The gear 12L (Figs. 4 and 6) through an exactly similar set of clutch connections drives a disk 18L under control of a second pair of start and stop magnets designated STL and SPL. The parts associated with this second clutch mechanism are identified with the same reference characters followed by the suffix L, while the corresponding parts have the suffix R for the first or right hand clutch mechanism.

Referring to Figs. 4 and 6, the disk 18R has integral therewith a gear 27R while the disk 18L has a similar gear integral therewith designated 27L. Between these two gears is a carry disk or wheel designated 30 secured to sleeve 15 and provided with an opening in which a pair of pinions 31 and 32 are mounted. The manner of mounting pinions 31, 32 is shown in Fig. 4a where it is seen that the pinions mesh with one another within the opening in wheel 30 and extend outwardly in opposite directions to mesh with gears 27L and 27R whose relative location is indicated in dotted lines in Fig. 4a. To support the pinions in the wheel 30, straps 30a are provided which extend across the opening on opposite sides of the wheel and carry the pivot studs of the pinions. The ratio of gear 27R to its pinion 31 is 2 to 1. However, as is well known, the particular ratio is immaterial and is chosen here for convenience of manufacture. The gears and pinions comprise a well known type of planetary gear structure, whereby advance of either disk 18R or 18L will advance disk 30 a proportional amount, that is, if either disk 18R or 18L is advanced a full revolution, disk 30 will be advanced a half revolution and, if both disks 18R and 18L are advanced a full revolution, disk 30 will advance a full revolution. Disk 30 is thereby advanced to any one of twenty rotative positions an amount representing the sum of the advances of the two disks 18L and 18R. Assume both gears 27L and 27R turn a full revolution together. As a result, pinions 31 and 32 do not rotate on their axes, but

5 their axes rotate about the center of gears 27R and 27L, carrying along disk 30. In other words, the entire differential assembly turns through a full revolution to advance disk 30 twenty steps. Disk 30 is provided with two portions 33 extending beyond the concentric part thereof and two notches 34 extending inside the concentric part.

10 Riding on the periphery of disk 30 is an arm 35 loosely pivoted on rod 36 and provided with a pin 37 in engagement with a contact blade 38. When disk 30 is in a rotative position representing any digit other than 8, 18, 9 or 19, lever 35 is in contact with the concentric portion of the disk and holds blade 38 in mid-position to establish an open condition of pairs of contacts 40 and 41. When the disk 30 is in a condition representing a setting of 8 or 18, one of the portions 15 33 lies under the nose of lever 35 and elevates pin 37, so that contacts 40 are closed. When the disk is in a position to represent the digit 9 or 19, the nose of lever 35 is in the recess 34 wherein pin 37 is lowered to permit closure of contact 41.

20 Also riding on the periphery of disk 30 is a pin 43 carried by a lever 44 pivoted on rod 36 independently of the lever 35. When disk 30 moves from its rotative position representing 9 or 19 to the position representing 10 or 0, the rising portion 33 will pass under pin 43 and momentarily elevate it to thereby rock lever 44 clockwise. To the left end of this lever is pivoted a spring pressed pawl 45 which will engage and rock a notched plate 46 pivoted on a stud 60. When the plate is rocked, a detenting pawl 48 will engage the lower one of the two notches at the right side thereof (Fig. 3) to hold the plate displaced while the pawl 45 returns. Integral with plate 46 is an arm 49 (Figs. 1 and 4) carrying a pin 50 normally occupying the position shown in these figures. When the plate 46 is rocked as explained, arm 49 and pin 50 are rocked to a mid-position indicated in broken lines in Fig. 4, wherein the pin has moved away from the contact blade 51 to effect opening of the pair of contacts 52 and closure of pairs of contacts 53 and 54. This is the position the parts will take if to the amount standing on disk 30 there is added an amount sufficient to cause a tens carry of one unit. If such added amount is of sufficient value to result in a tens carry of two units, the 25 disk 30 will advance sufficiently so that the second rise 33 will elevate pin 43 a second time and pawl 45 will reengage plate 46 beneath its lower tooth and rock the plate through an additional angle. This will result in rocking lever 49 and pin 50 in a third position indicated at Fig. 4 in which the pin will cause closure of contacts 55 and reopening of contacts 54. The manner in which the several carry contacts, when adjusted in their several positions, control the operation of the accumulating mechanism will be explained in connection with the circuit diagram.

30 In Figs. 2 and 6, the sleeve 15 which is integral with the carry disk 30 has secured thereto a pair of brushes 56 which contact the readout device comprising individual segments 57 and common segment 58. The brushes represent by their setting the digit value standing on the disk. Thus, if the disk is in its 0 rotative position, one of the brushes 56 is in contact with the 0 segment 57 and the other is in contact with the common segment 58 to provide a current path between the two.

35 Referring to Figs. 1 and 6, the plate 46 is freely rotatable on a rod 60 upon which there is also freely rotatable a lever 61 from which a pin 62 projects into the plane of the pawl 45 and a sec-

ond pin 63 projects into the path of holding pawl 48. When lever 61 is rocked clockwise as viewed in Fig. 1, these pins will engage their respective pawls to rock them out of engagement with plate 46, which will thereupon under spring influence return to the position of Fig. 1. This restoring action takes place after the carry period in the cycle and is effected as follows.

A lever 64 pivotally mounted on rod 65 has a cam slot 66 embracing a pin 67 in lever 61 and also has an extension 68 lying in the path of the pin 69 carried by gear 12R. Thus, when pin 69 strikes lever 68 near the end of the revolution of the gear, lever 64 is rocked clockwise against the action of its spring 70 and cam slot 66 will rock lever 61 clockwise to effect unlatching of plate 46.

In the operation of the accumulator, the normal or home position of each denominational disk 30 is with the disk in its rotative position representing 9, so that in effect the accumulator when reset contains the 9's complement of 0. When an amount is to be additively entered, the 9's complement of such amount is added and, when the amount is to be subtractively entered, it is directly added. The operation may best be explained by reference to a particular example. Let it be assumed that the accumulator initially contains the true amount 74333, to which amounts 93121 and 21141 are to be concurrently added, resulting in the total 188595. In this case the several disks 30 of the accumulator are in rotative positions in the several orders representing the 9's complement 925666.

The two amounts to be added are perforated in record card C (Fig. 7b) and the card is in readiness to pass the brushes LB. The amount in the left hand portion of the card is to be entered in the left side of the accumulator and the amount in the right hand portion is to be entered in the right side of the accumulator. Plug connections 71 are made between plug sockets 12 of brushes LB and sockets 73, as represented for the units order brushes, for example. If the amount in the left portion of the card is to be added, switches L14 are closed and, if the amount in the right hand portion is to be added, switches R14 are closed. Since for the example chosen both amounts are to be added, switches L14 and R14 are in closed position as shown in Fig. 7b. With this preliminary switch setting made, main drive shaft 10 is given a single revolution during which the contact devices represented in Fig. 8 will operate to control the several circuit connections.

During the cycle as noted from Fig. 8, the contacts C10 first close to complete a circuit connection from one side of the line designated 75, through contacts C10, the L14 and R14 switches to the relays designated +L and +R to the other side of line 76. These relays will accordingly remain energized for the period indicated in Fig. 8, which is co-extensive with the period during which the digit perforations representing 9 to 1 pass the brushes LB. These relays shift related contacts designated with the same reference character as the relay followed by a lower case letter.

In Fig. 7a, contacts C11 close concurrently with the sensing of the 9 hole position in the card and complete a circuit from line 75, contacts C11, wire 77, in parallel through all of the relay contacts +Ra (now shifted), thence through all of the contacts designated REa (in normal position), through all of the start magnets STR to line 76.

Concurrently, the circuit branches from wire 77, through all of the +La contacts (now shifted),

through all of the contacts REb (in normal position), through the start magnets STL to line 76. Accordingly, the entering clutch devices in both the left and right hand sections of all denominational orders are simultaneously operated, and rotation of all the disks 18L and 18R will commence, and will continue until a perforation is sensed in the related card column. In the units order (Fig. 7b) for example, such rotation will 10 continue until the 1 hole is sensed, at which time a circuit is completed for the right hand amount, traceable from line 75, contact roller 78, 1 perforation in card C, right hand brush LB, plug socket 72, connection 71, socket 73 farthest to the right, wire 79, the lower set of contacts +Ra (now shifted), magnet SPR to line 76. This magnet is thus energized eight cycle points after the initial energization of magnet STR, and accordingly the corresponding disk 18R will have been advanced eight steps, which is the 9's complement of the 1 perforation sensed. For the left hand amount, the circuit is similarly traceable from line 75, contact roller 78, 1 perforation in the card, brush LB farthest to the right in the left hand 20 group, socket 72, connection 71, socket 73, wire 80, lower relay contact +La (now shifted) and magnet SPL to line 76.

In a similar manner for other digital values, the circuit is completed to magnet SPL or SPR 30 to advance the related disk 18L or 18R an amount representing the 9's complement of the value sensed. Where the digit punched is 9, the impulse from the card will occur simultaneously with the impulse to the related start magnet from 35 contacts C11, so that in the related position the adding disk does not advance, inasmuch as concurrent energization of both start and stop magnets in an order will not operate the related armature. In card columns containing 0's or 40 columns containing no punching, a circuit is completed at the 0 time in the cycle from line 75 (Fig. 7a), contacts C12, wire 81, lower set of contacts +La (back in normal position at this time) and magnets SPL to line 76. The circuit from 45 wire 81 also extends through contacts +Ra and magnets SPR to line 76. At the time the contacts C12 close, the +L and +R relays are de-energized, so their contacts are back in normal position enabling the completion of circuits 50 therethrough to the stop magnets, and those which have not been previously energized will now be effective to uncouple the related adding disks after nine steps of advance. In those positions in which energization has previously taken 55 place, the impulse will of course be idle.

The setting of the accumulator wheels or disks 30 will be represented as follows:

Setting of disk 30 (initially)	9	2	5	6	6	6
Advance of disk 18R	9	0	6	8	7	8
Advance of disk 18L	9	7	8	8	5	8

Position of disk 30 before

carry	7	9	9	2	8	2
Carries	1	2	2	2	2	2
	8	1	1	4	0	4

In the above table it is indicated that the disks 30 advance to represent a setting of 799282 and in moving to such setting, the carry contacts of 70 Fig. 4 will be shifted in response to the movement of the disks 30. Since adding is effected complementarily, provision is made for so-called highest-to-lowest order carry, whereby in the above example a 2 is carried into the units order 75 under control of the carry out of the highest

order. In the units order (Fig. 7b), the pin 50 will be in its lowermost position, as diagrammatically represented, to effect closure of contacts 53 and 55 and opening of contacts 52 and 54, while pin 37 is in mid-position to hold contacts 40 and 41 open. In the tens order pin 50 has moved to mid-position as indicated, and pin 37 is in position to close contacts 40, since in this order the disk is standing in its 18 position. In the hundreds order the pin 50 is in lowermost position while pin 37 holds contacts 40 and 41 open.

In the thousands order, pin 50 is in mid-position and pin 37, due to a 19 standing in this order, is in position to close contacts 41. In the tens of thousands order pin 50 is in its uppermost position representative of no tens carry, while pin 37 is in position to close contacts 41 representative of a 9 standing in this order. In the highest order, pin 50 is in its lowermost position representing a carry of 2, while pin 37 holds contacts 40 and 41 open. This then diagrammatically represents the several carry contact settings for the problem chosen, and through the circuit connections now to be traced appropriate additional carry entries will be made.

As noted in Fig. 8, the several relays +L and +R are deenergized as well as the relays designated -L, -R and RE so that the contacts thereof are in the positions shown, at the carry time in the cycle. Accordingly, when contacts C13 (Fig. 7a) close at the time indicated in Fig. 8, a circuit is completed from line 75, contacts C13, wire 83 (Fig. 7b), to the units order, thence through contacts 53, wire 84 in this order, contacts designated -Ra, +Ra, REa, magnet STR in the tens order to line 76. As a result, the clutch in the right hand section of the tens order is coupled to drive its disk 18R. At the same time a second circuit is completed, traceable from the wire 83 (Fig. 7b), through contacts 55 in the units order, wire 85, contacts designated -La, +La, REb, magnet STL to line 76. Thus, the disk 18L in the tens order is coupled concurrently with the disk 18R. After one step of movement, contacts C14 (Figs. 7a and 8) close to complete a circuit from line 75, contacts C14, wire 81, contacts +La and +Ra to energize all of the SPL and SPR magnets which will result in uncoupling after the entering disks 18L and 18R have advanced one step. Since in the tens order both left and right hand disks have been advanced one step, the disk 30 associated therewith is advanced two steps from its 2 to its 4 position as indicated in the table above.

In the tens order it is noted that disk 30 initially stood in its 18 position, and contacts 40 in such order are closed, so that the circuit just traced through wire 85 (Fig. 7b) will branch through the contacts 40 in the tens order, through contacts 54 and the wire 85 to the hundreds order (Fig. 7a), where it continues through contacts -La, +La and contacts REb in the hundreds order to energize magnet STL to add a 1 in the left hand disk of the hundreds order.

Referring back to Fig. 7b, contacts 53 in the tens order are closed in accordance with a 1 carry condition, so that there is a circuit completed from wire 83, contacts 53, wire 84 extending over to the hundreds order and thence through contacts -Ra, +Ra, REa to magnet STR to add a 1 in the right hand section of the hundreds order. In this manner a 2 is added to the 2 standing in the hundreds order of the accumulator.

In the hundreds order a circuit is traceable from wire 83, through the closed contacts 53 to energize the magnet STR of the thousands order through the wire 84 in this order, and the now familiar circuit paths. Since in the thousands order the disk 30 stands at 19, its contacts 41 are closed so that the circuit through wire 84 branches through the contacts 41 in the thousands order, its closed contacts 54 and wire 85 to the magnet STL in the tens of thousands order. In the hundreds order the contacts 55 are closed, so that the circuit therethrough will energize magnet STL in the thousands order, resulting in advance of this order from 19 to 1. The single carry setting in the thousands order represented by closure of contacts 53 will enable completion of a circuit through the STR magnet in the tens of thousands order. As already traced, the corresponding magnet STL is also energized as a result of the carry-on-carry of the contacts 41 in the thousands order, so that a 2 is added to the 9 setting of the tens of thousands order advancing this to 11.

In the highest order, contacts 55 are closed to represent a double carry and in this order a circuit is traceable from wire 83 to contacts 55, wire 87 extending to Fig. 7b, where it passes through contacts -La, +La and REb to magnet STL in the units order to add a 1 in the left hand part. In the highest order the contacts 53 are also closed so that a second circuit is traceable from the wire 83, contacts 53, wire 88, which extends over to Fig. 7b, and thence through contacts -Ra, +Ra and REa to magnet STR of the units order. Thus, a 2 which might be called an elusive 2 is entered in the units order to advance the setting of 2 to 4. Following completion of these carry circuits, the amount standing on the disks 30 is 811404 which is the 9's complement of the true result.

When an amount is to be subtracted, switch L89 or R89 (Fig. 7b) is closed prior to the movement of the card past the brushes LB. Accordingly, when contacts C10 close, the relay -L or -R or both will be energized for the period indicated in Fig. 8 and related contacts will be in shifted position during the portion of the cycle during which entries are made from the card.

Assuming, for example, that the amount in the right hand portion of the card is to be subtracted, switch R89 is closed and relay -R will be energized. The magnets STR will now not be energized when contacts C11 close, inasmuch as the circuit from these contacts through wire 77 is interrupted by the contacts +Ra which are now in normal position. These magnets become energized at the time that a hole is sensed in the related card column. Thus, for example, when a perforation in the units column of the right hand section of the card is sensed, a circuit is completed from line 75, contact roller 78, perforation in the card, brush LB, socket 72, connection 71, socket 73, wire 79, contacts -Ra in the units order (now shifted), contacts +Ra, REa and magnet STR to line 76. Thus, the related disk 18R will commence to rotate at the time the hole is sensed.

At the 0 time in the cycle, when contacts C12 close, a circuit is completed through wire 81 to all of the SPR magnets as previously traced, so that the adding disk is advanced a number of steps equal to the true value of the digit sensed, and as the result balance disks 30 will be advanced accordingly and will operate carry contacts in the manner already explained. After the entry por-

tion of the cycle, the carry start impulse of contacts C13 is initiated and the carry stop impulse through contacts C14 follows one step later to adjust the result disks so they represent the complement of the true value of the algebraic summation. In the present arrangement, it is assumed that the final result is always a positive value, so that the setting on the disks 30 is always a complement.

Briefly summarizing, when an amount is to be added in the accumulator, the start magnets are initially energized to commence adding 9's in all orders, and the entering operation is interrupted upon sensing of the value perforations, so that the adding disks advance an amount representing the 9's complement of the value to be added. When an amount is to be subtracted, the start magnets are energized upon the sensing of the perforations and the rotation is interrupted at the 0 point in the cycle so that the adding disks advance an amount representing the true value of the amount to be subtracted.

Result readout and reset

As explained in the mechanical description, the result disk 30 advances readout brushes 56 which, by their position with respect to the segments 57 and common conductor 58 represent the value (complement) standing on the disks 30. When it is desired to read out the amount standing in the accumulator, switches 90 are closed and shaft 10 is given a single revolution during which the contacts designated C1 to C9 in Fig. 8 close in the order indicated. Accordingly, with brush 56 in the units order set to represent the complement 4, a circuit will be traceable from line 75 (Fig. 7b), through contacts C5 at the 5 time in the cycle, the 4 segment 57, brush 56, conductor 58, switch 90, and a magnet 91 to line 76. Magnet 91 operates printing mechanism responsive to timed impulses to cause a type bar to print the character 5 in the well known manner.

If it is desired to reset the accumulator, the switch 92 (Fig. 7b) is closed before effecting the rotation of shaft 10, so that when such rotation commences, contacts C10 will energize relay RE and cause shifting of related relay contacts. Then, during the cycle when contacts C5 close, the circuit extends from line 75, through contacts C5, the 4 segment 57 and brush 56 to common conductor 58 as before, but branches upwardly from the conductor through a wire 93, the contacts REa (now shifted), to magnet STR and line 76. Accordingly, rotation of the adding disk 18R is commenced. Five steps later in the cycle the contacts C12 close and the stop circuit already traced through wire 81 is completed to energize magnet SPR to uncouple the driving connection, at which time the disk 30 will have advanced to its 9 position. The readout and resetting circuits in the other denominational orders will be completed in a similar manner. Specifically, in the tens order where the brush 56 is set at 0 (complement), the circuit is completed to the magnet STR in this order through contacts C9 and brush 56 in the 0 position, and the magnet SPR will be energized after nine steps of movement of the corresponding disk 30, so that this disk is also brought to the 9 position.

The net result is that during this resetting cycle all the adding disks 30 are advanced to their 9 positions which is the normal or home position of the disks. By operating the device with a home position in which 9's stand in all orders, the resetting and readout operations are

effective during a single revolution of the drive shaft, since both the readout and reset circuits may be completed during the one cycle.

While there have been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. A denominational order of an accumulator comprising a pair of entering wheels, each rotatable differential amounts to represent digital entries, an adding wheel having twenty rotative positions, differential gear connections between said adding wheel and said pair of entering wheels, means for advancing each entering wheel a selected differential amount, whereby the adding wheel will be advanced through a number of rotative positions equaling the sum of the digits entered in entering wheels, a plurality of variably adjustable contacts controlled by said adding wheel and adjustable thereby in one manner when the wheel is advanced to a rotative position representing an entry of 8, in a second manner when the wheel is advanced to a rotative position representing an entry of 9, in a third manner when the wheel is advanced to a rotative position representing an entry of 10 to 17, in a fourth manner when the wheel is advanced to a rotative position representing an entry of 18, in a fifth manner when the wheel is advanced to a rotative position representing an entry of 19, and in a sixth manner when the wheel is advanced to a rotative position representing an entry of 20, and means controlled by said plurality of contacts for causing said advancing means to advance the entering wheels in accordance with carry requirements.

2. In a cyclically operating machine, an accumulator in which amount entries are made in one part of a cycle and tens carries are made in a following part of the same cycle, each denominational order of which accumulator comprises

50 a pair of entering wheels, rotatable differential amounts to represent digital entries therein, an adding wheel having twenty rotative positions, and differential gear connections between the entering wheels and the adding wheel, advancing means for the entering wheels, control means operative during said one part of a cycle to cause the advancing means to effect concurrent entry of selected digits into said entering wheels, whereby the adding wheel in each order will be advanced through a number of rotative positions equaling the sum of the digits entered in the related entering wheels, carry control means for each order settable by the related adding wheel in accordance with the entry therein at the end of said one part of a cycle, and means effective during the carry part of the cycle and controlled by the carry control means of any lower order to cause the advancing means to effect entry of a unit into either or both the entering wheels

60 65 70 75 of said one part of a cycle, and means effective during the carry part of the cycle and controlled by the carry control means of any lower order to cause the advancing means to effect entry of a unit into either or both the entering wheels of the next higher order in accordance with tens carry requirements.

3. In a machine of the class described, an accumulator having a series of denominational orders adding wheels, a pair of driving wheels for each adding wheel, differential gear connec-

11

tions between each adding wheel and the pair of related driving wheels, a main drive shaft, electro-magnetic coupling means and control means therefor for concurrently coupling the driving wheels to the main drive shaft during one part of a revolution thereof for selected extents of rotation whereby each adding wheel is driven an extent representing the sum of the extents for which the related pair of driving wheels is driven by the main shaft, a set of contacts for each adding wheel set to different positions by the wheel, means controlled by said main drive shaft and by the set of contacts of an adding wheel, during a later part of a revolution of the shaft for causing said coupling means to couple either or both of the driving wheels of the next higher order to the drive shaft according to the position of the said lower order wheel.

4. The invention set forth in claim 3 in which additional contacts are provided in each set and in which the last named means is further controlled by the said additional contacts of the said next higher order wheel to cause the coupling means to couple either or both of the driving wheels of the still higher order to the drive shaft according to the position of the said higher order wheel.

5. In a machine of the class described, an accumulator having a series of denominational ordered adding wheels, a pair of driving wheels for each adding wheel, differential gear connections between each adding wheel and the pair of related driving wheels, a main drive shaft, electromagnetic coupling means and control means therefor for concurrently coupling the

12

driving wheels to the main drive shaft during one part of a revolution thereof for selected extents of rotation whereby each adding wheel is driven an extent representing the sum of the extents for which the related pair of driving wheels is driven by the main shaft, a set of contacts for each adding wheel set to different positions by the wheel, means controlled by said main drive shaft and by the set of contacts of the highest order adding wheel during a later part of a revolution of the shaft for causing the said coupling means to couple either or both of the driving wheels of the lowest order to the drive shaft according to the position of the said highest order wheel, and means controlled by said main drive shaft and by the set of contacts of a lower order adding wheel, during said later part of a revolution of the shaft, for causing the coupling means to couple either or both of the driving wheels of the next higher order to the drive shaft according to the position of the lower order wheel.
